A technical line drawing of a mechanical assembly. On the left, a circular component with a central hole and a ribbed outer edge is labeled 11. A horizontal bar extends to the right from this component, with a section labeled 12. A vertical post 32 is attached to the top of the bar. A horizontal slot 30 is cut into the bar, and a rectangular block 31 is positioned within this slot. The drawing is signed 'Fig. 3.' in the upper left area.

UNITED STATES PATENT OFFICE.

FLOYD C. WEAVER, OF WASHINGTON, DISTRICT OF COLUMBIA.

GRINDING AND LAPING MACHINE.

Application filed May 10, 1922. Serial No. 559,882.

To all whom it may concern:

Be it known that I, FLOYD C. WEAVER, a citizen of the United States, residing at Washington, District of Columbia, have invented certain new and useful Improvements in a Grinding and Lapping Machine, of which the following is a specification, reference being had therein to the accompanying drawings.

- 10 The object of this invention is to provide a driving mechanism for moving a lapping plate relative to a work carrying plate in a desired orbit and for varying the orbit and the position of the orbit in respect to the 15 work carrying plate and thereby cause the lapping plate to follow particular processes of operation based upon the specific physical behavior of the materials being worked upon.
- 20 With these and other objects in view, my invention comprises certain novel combinations, constructions and arrangements of parts as will be hereinafter described, illustrated in the accompanying drawings, and 25 more particularly pointed out in the appended claims.

In the drawings:

- Figure 1 is a plan view of the lapping machine showing the relative arrangement 30 of the lapping plate and work carrying plate to the driving mechanism and its control features.

Figure 2 is a vertical section of the lapping machine shown in Figure 1 taken along the line 2—2 in the direction of the arrows. This view shows the relative positions of the lapping plate and the work carrying plates to the driving mechanisms.

Figure 3 is a vertical section of the lapping machine shown in Figure 1 taken along the line 3—3 in the direction indicated by the arrows. This view shows the main driving shafts.

Figure 4 is a vertical section of the lapping machine shown in Figure 1 taken along the line 4—4 in the direction indicated by the arrows. This view shows the driving eccentric plate for operating the stroking pin actuating the lapping plate.

Figure 5 is a vertical section of the lapping machine shown in Figure 1 taken along the line 5—5 in the direction indicated by the arrows. This view shows the second driving eccentric plate for operating the stroking pin actuating the lapping plate,

also showing the manner of support of bearing and driving mechanism essential for adjustment of the eccentric axis relative to axis supporting work carrying plate when varying position of path of the pin actuating the 60 lapping plate.

Figure 6 is a section of the eccentric plates showing the essential details of construction which enable the adjustments to be made which are necessary in obtaining the proper 65 movement of the pin actuating the lapping plate over the work carrying plate.

Referring to Figure 1, the lapping plate 2 is actuated by the pin 3 over the work carrying plate 1. The pin 3 is securely clamped 70 in the block forming the end of the bar 20. At the opposite end of bar 20 is the hinge fork coupling to the bearing collar 19 fitting upon the eccentric driving pin 18. Fitting in and upon bar 20 is the ball socket bearing block 21 capable of being clamped firmly in adjustment along the slot in bar 20 by the screws 22. This bearing block 21 receives the ball end of the bar 23, clamped securely in adjustment in the bar 25 by the 75 screws 24. The outer end of bar 25 carries a hinge fork coupling to the bearing collar 27 fitting upon the eccentric driving pin 26. Thus the pin 3 is actuated by the combination 80 of the motions of the eccentric driving pins 18 and 26.

Referring to Figures 2, 3 and 4 in conjunction with Figure 1, the driving pin 26 is secured in adjustment in the slot 29 of the eccentric plate 28 which in turn is secured 90 firmly to the vertical axis 42. Securely attached to axis 42 is the worm wheel or gear 43 in mesh with the driving worm or pinion 30 on driving shaft 31. This driving shaft 31 carries the main driving gear 32 in mesh with the main driving pinion 36 connected by the clutch 37 operated by the lever 38 to the main drive shaft 35 which carries the power pulley 34. The drive shaft 31 also carries the bevel gear 33 in mesh with bevel gear 12 securely attached to drive shaft 11. This drive shaft 11 carries the worm or gear pinion 13 free to be moved along its axis yet positively driven by the spline keyway 14.

Referring to Figure 5 in connection with Figure 1 the worm or pinion 13 is secured between the arms of the yoke 15 forming also a bearing for drive shaft 11, as well as the bearing for axis 49 which carries the 100 firmly secured eccentric plate 16. This axis 110

49 is firmly secured to the driving worm wheel or gear 48 in mesh with the worm or pinion 13 on the shaft 11. This yoke 15 also carries the threaded screw bearing for the screw shaft 39 which has at its outer end the hand wheel 40. The yoke 15 is free to slide along the guides or ways 47 upon the operation of hand wheel 40. Thus the axis 49 and the eccentric plate 16 mounted upon the yoke 15 may be moved at will along a direction parallel to axis of driving shaft 11 by the operation of hand wheel 40. The driving shaft 11 is connected at will of operator to shaft 6 by clutch 8 actuated by lever 9. This driving shaft 6 carries the worm or gear pinion 5 and the hand wheel 7.

Referring to Figure 2 in conjunction with Figure 1 the worm or pinion 5 is meshed with the worm wheel or gear 4 secured upon the axis 45 which is in turn firmly secured to work carrying plate 1. Thus, at the will of the operator, axis 49 and eccentric plate 16 can be shifted by hand wheel 40 toward or away from the work carrying plate 1 and axis 45, at all stages of the machine operation. Also by disengaging shaft 6 from shaft 11 by clutch 8, the work carrying plate 1 is then free to be operated by hand wheel 7.

Referring to Figure 6 in conjunction with Figure 1, the eccentric driving plates 16 and 28 are detailed in such a manner that the relative angular relation of the slots carrying the driving pins 18 and 26, respectively, may be adjusted at will. The driving axis 55 is firmly secured to bearing plate 54. The plate 52, carrying the slot for driving pin 26 and its securing nut 50, is clamped for any relative angular adjustment by screws 51, drawing the ring 53 against the flange of 54, clamping it firmly to the under face of 52.

Thus the pin 3 actuating the lapping plate 2 is driven by the two eccentric plates 28 and 16 in a prescribed path, and which path is shifted at will by operating hand wheel 40 along any portion of the work carrying plate. Also by operating the hand wheel 7 in conjunction with the hand wheel 40 the lapping effort of plate 2 is localized to any desired portion of the work carrying plate 1.

While I have described the preferred embodiment of my invention, and have illustrated the same in the accompanying drawings, certain minor changes or alterations may appear to one skilled in the art to which this invention relates, during the extensive manufacture of the same and I, therefore, reserve the right to make such alterations or changes as shall fairly fall within the scope of the appended claims.

The invention having been described, what is claimed is:

1. In a grinding and lapping machine of

the character described, the combination of a work carrying plate, means for supporting said work carrying plate, a lapping plate positioned above said work carrying plate, a pin engaging said lapping plate, a bar connected to said pin, means for oscillating said bar, driving means connected to the rear end of said bar, whereby said lapping plate may be moved in a variable manner over said work carrying plate, and means for bodily advancing or retracting said driving means, whereby said lapping plate may be caused to work only upon certain portions of the work carrying plate, as and for the purposes set forth. 70

2. In a grinding and lapping machine of the character described, the combination of a work carrying plate, means for supporting said work carrying plate, a lapping plate positioned above said work carrying plate, a pin engaging said lapping plate, a bar connected to said stroking pin, means for oscillating said bar, an eccentric plate carried adjacent the rear end of said bar, means connecting said plate to said bar, means for driving said plate, whereby said bar will be shifted for stroking said lapping plate in a variable manner, and means for bodily advancing or retracting said eccentric plate, whereby said lapping plate will be caused to operate over certain portions of the work carrying plate as desired, as and for the purposes set forth. 85

3. In a grinding and lapping machine of the character described, the combination of a work carrying plate, means for supporting said work carrying plate, a lapping plate positioned above said work carrying plate, a pin engaging said lapping plate, a bar connected to said pin, means for oscillating said bar, an eccentric plate carried adjacent the rear end of said bar, means connecting said plate to said bar, means for driving said plate, and means for bodily moving said plate and said driving means including a manually operated screw shaft. 100

4. In a grinding and lapping machine of the character described, the combination of a work carrying plate, means for supporting said work carrying plate, a lapping plate positioned above said work carrying plate, a pin engaging said lapping plate, a bar connected to said pin, means for oscillating said bar, an axis having a gear thereon, an eccentric plate supported upon said axis, means connecting said bar to said eccentric plate, a drive shaft having a worm keyed thereon and slidably therealong and engaging said gear, and means for shifting said axis and said worm, as and for the purposes set forth. 115

5. In a grinding and lapping machine of the character described, the combination of a work carrying plate, means for supporting said work carrying plate, a lapping plate positioned above said work carrying plate, a

- pin engaging said lapping plate, a bar connected to said pin, means for oscillating said bar, an axis having a gear thereon, an eccentric plate supported upon said axis, 5 means connecting said bar to said eccentric plate, a drive shaft having a worm keyed thereon and slidable therealong and engaging said gear, a movable yoke member engaging said axis and said worm, and manually 10 operated means for holding said yoke member in an adjusted set position, as and for the purposes set forth.
6. In a grinding and lapping machine of the character described, the combination of a 15 work carrying plate, means for supporting said work carrying plate, a lapping plate positioned above said work carrying plate, a pin engaging said lapping plate, a bar connected to said pin, means for oscillating said 20 bar, an axis having a gear thereon, an eccentric plate supported upon said axis, means connecting said bar to said eccentric plate, a drive shaft having a worm keyed thereon and slidable therealong and engaging 25 said gear, a pair of parallel slides extending upon opposite sides of said axis, a yoke member movable along said slides and having a hub surrounding said axis and spaced arms engaging the ends of said worm, said yoke member also having a bearing, and a manually operated screw shaft engaging 50 said bearing, whereby the shaft may be turned for shifting and then retaining in an adjusted position said axis and said worm, as and for the purposes set forth.
- In testimony whereof I hereunto affix my 55 signature.

FLOYD C. WEAVER.
